CLAIM

The ornamental design for a housing for an electronic bar code reader, as shown and described.

DESCRIPTION

FIG. 1 is a top, front, left side perspective view of a housing for an electronic bar code reader showing our new design;

FIG. 2 is a front elevational view thereof;

FIG. 3 is a right side elevational view thereof;

FIG. 4 is a rear elevational view thereof;

FIG. 5 is a top plan view thereof;

FIG. 6 is a bottom plan view thereof;

FIG. 7 is a top, front, left side perspective view of a second embodiment of our new design;

FIG. 8 is a front elevational view thereof;

FIG. 9 is a top plan view thereof.

The undisclosed views of the second embodiment are similar in appearance to those of the first embodiment.

FIG. 1.

FIG. 2.

FIG. 3.

FIG. 4.

FIG. 5.

FIG. 6.

FIG. 7.FIG. 8.FIG. 9.
